US00D676767S

(12) **United States Design Patent**
Tamborra

(10) **Patent No.:** **US D676,767 S**
(45) **Date of Patent:** **** Feb. 26, 2013**

(54) **DIGITAL REFRIGERATION
TIME/TEMPERATURE MONITOR**

7,360,369 B2 * 4/2008 Tamborra 62/129
2006/0074586 A1 * 4/2006 Kautz et al. 702/130
2008/0163629 A1 * 7/2008 Chen 62/129

(76) Inventor: **Dominick Tamborra**, Deltona, FL (US)

* cited by examiner

(**) Term: **14 Years**

(21) Appl. No.: **29/425,781**

Primary Examiner — Antoine D Davis

(22) Filed: **Jun. 27, 2012**

(74) Attorney, Agent, or Firm — Edwards Wildman Palmer LLP; Howard M. Gitten

(51) LOC (9) Cl. **10-04**

(57) **CLAIM**

(52) U.S. Cl. **D10/49; D10/50**

The ornamental design of a digital refrigeration time/temperature monitor, as shown and described.

(58) **Field of Classification Search** D10/49-50;
62/125, 126, 127, 129, 157, 231; 340/585,
340/588; 702/63, 130, 182

DESCRIPTION

U.S. PATENT DOCUMENTS

4,041,723 A *	8/1977	Weibel et al.	62/126
4,369,634 A *	1/1983	Ratto	62/126
5,711,160 A *	1/1998	Namisniak et al.	62/125
5,969,606 A *	10/1999	Reber et al.	340/540
6,771,177 B2 *	8/2004	Alderman	340/585

FIG. 1 is a top perspective view of the digital refrigeration time/temperature monitor showing a new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
